(57) **CLAIM**

The ornamental design for a socket of hand tool, as shown and described.

DESCRIPTION

FIG. 1 is a perspective view of socket of hand tool showing my new design.

FIG. 2 is a top view thereof;

FIG. 3 is a bottom view thereof;

FIG. 4 is a cross sectional view along the A-A line in FIG. 2;

FIG. 5 is a perspective view thereof;

FIG. 6 is a front view thereof;

FIG. 7 is a rear view thereof;

FIG. 8 is a top view thereof;

FIG. 9 is a bottom view thereof;

FIG. 10 is a partial enlargement top view thereof; and,

FIG. 11 is a partial enlargement bottom view thereof.

1 Claim, 8 Drawing Sheets(56)
